Primary Examiner — Lucy Lieberman(74) *Attorney, Agent, or Firm* — Philip H. Gottfried, Esq.; Amster, Rothstein & Ebenstein LLP(57) **CLAIM**

The ornamental design for a watch, substantially as shown and described.

DESCRIPTION

FIG. 1 is a top perspective view of a watch showing my new design;

FIG. 2 is a bottom perspective view thereof;

FIG. 3 is a left side view thereof;

FIG. 4 is a right side view thereof;

FIG. 5 is a front view thereof;

FIG. 6 is a rear view thereof.

FIG. 7 is a top view thereof; and,

FIG. 8 is a bottom view thereof.

The broken lines in the drawings are used to show a watch band that does not form part of the claimed design.
